Atty's.

UNITED STATES PATENT OFFICE.

FRED ARN, OF CHATTANOOGA, TENNESSEE, ASSIGNOR TO J. M. CARD LUMBER CO., OF CHATTANOOGA, TENNESSEE, A CORPORATION OF TENNESSEE.

CHOCK-BLOCK.

1,400,786.

Specification of Letters Patent. Patented Dec. 20, 1921.

Application filed August 9, 1920. Serial No. 402,126.

To all whom it may concern:

Be it known that I, FRED ARN, a citizen of the United States, and resident of Chattanooga, Tennessee, have invented certain new 5 and useful Improvements in Chock-Blocks, of which the following is a specification.

My invention relates to chock blocks for use in transporting automobiles, to set 10 against the wheels for retaining the automobile against displacement, on the floor of the car, used in shipping automobiles from the factory.

In the accompanying drawings:

Figure 1 is a perspective view of a chock 15 block embodying the invention.

Fig. 2 is a rear view.

Fig. 3 is a side elevation.

In these drawings the chock block is represented as of substantially a known form as 20 to its general characteristics. One of my objects is to provide means which will enable unskilled labor to be employed in affixing the chock blocks in place and will insure uniformity in the performance of the work in 25 this particular. In carrying out the invention, I provide a series of nail holes in the sides of the block indicated at 1, these nail holes inclining downwardly and toward the rear face 2 of the block, and therefore 30 in the direction, generally speaking, in which the strain is imposed upon the block from the wheel of the automobile. The front face of the block is curved longitudinally and also this face is grooved laterally so as to 35 fit the rounded surface of the tire.

At the rear of the block I provide means whereby the workman will be guided in his application of the nails, this means consisting of a plurality of recesses 3 having in 40 dents or holes 4 to receive the nail.

The recesses are formed by a boring tool and this tool is set at an inclination to the rear face of the block in order to form these recesses, and hence the walls of these recesses are curved to conform to the boring tool and walls 5 are left between them which will serve to preserve the strength of the block at these points and prevent splitting.

There is a nail hole at the bottom of each recess so that the workman cannot go astray 50 in applying the nails, and further, he will naturally set the nail at substantially a right angle to the bottom of the recess, which is inclined downwardly and rearwardly and thus the nail will be driven at the proper 55 angle to insure its full holding quality. The nail holes which are formed in the side of the block insure the placing of the nails at the proper angle and at the proper height from the bottom of a block so that the manufacturer is enabled to determine for himself 60 where the nail shall go through and the presence of these nail holes will insure uniformity of work on the part of the workman, and will enable him to carry on the 65 work with greater rapidity than otherwise would be the case. Were these nail holes not provided, a careless workman might start them at a point only slightly above the lower face of the block or even though he 70 placed the point of the nail at the proper height on the smooth side of the block, the nail might slip when the first blow was applied and not catch into the wood until its point had reached a position considerably 75 below the proper point for nailing as determined by the manufacturer of the block.

It will be seen from the above that with this block, the side nails incline downwardly and rearwardly, while the rear nails incline 80 downwardly and forwardly and the combined effect of these two sets of nails is to securely lock the block to the floor of the car.

I claim as my invention:

A chock block for automobiles or the like consisting of a solid block of wood, having a flat horizontal base and parallel sides perpendicular to the base, said block having in its parallel sides a plurality of nail openings inclining inwardly, downwardly and rearwardly, the said block having a curved front face adapted to bear upon the tire of the automobile, substantially as described.

In testimony whereof, I affix my signature. 95

FRED ARN.
